tion of Delaware

Application April 16, 1940, Serial No. 329,938

12 Claims. (Cl. 120—29)

This invention relates to copyholders, and more particularly to copyholders of the type which may be readily collapsed.

The primary object of the present invention is to provide an improved copyholder which may be readily collapsed when not in use and which is comparatively simple and inexpensive to manufacture and yet highly effective and reliable in use.

A further object of the present invention is to provide a copyholder having a copyholding member mounted on a carrier which may be moved on a support between collapsed and operative positions with improved controlling mechanism for the copyholding member which is jointly carried by the base and carrier with interconnecting means permitting the carrier to be readily moved to its collapsed position.

A still further object of the present invention is to provide a copyholder of the above type having means for returning the copyholding member to its normal position on the carrier as the carrier is moved to its collapsed position.

To the above and other ends which will hereinafter appear, the invention consists in the features of construction, arrangements of parts, and combinations of devices set forth in the following description and particularly pointed out in the appended claims.

In the drawings:

Fig. 1 is a side view of a copyholder constructed in accordance with the present invention and shown in operative position with relation to a typewriting machine, the view showing the collapsed position of the carrier and the copyholding member in full lines and the operative position thereof in dotted lines.

Fig. 2 is a rear elevational view of the copyholder with a portion of the rear carrier plate broken away.

Fig. 3 is an enlarged fragmentary section through the upper portion of the copyholder taken substantially on line 3—3 of Fig. 2.

Fig. 4 is another enlarged fragmentary section taken substantially on line 4—4 of Fig. 2.

Fig. 5 is still another enlarged fragmentary section taken substantially on line 5—5 of Fig. 2 with the copyholding member shown in its fully raised position.

Fig. 6 is an enlarged horizontal section through the copyholder taken substantially on line 6—6 of Fig. 2.

Fig. 7 is another enlarged horizontal section taken substantially on line 7—7 of Fig. 2.

Fig. 8 is a fragmentary horizontal section taken substantially on line 8—8 of Fig. 2.

The particular copyholder to which the invention has been applied in the present instance is of the type wherein the copy sheets are secured to a copyholding member and are intermittently moved past a stationary line indicator. In this type of copyholder, the copyholding member and line indicator are necessarily positioned when in use a considerable distance above the top of an ordinary typewriter, and the usual folding cabinet in a typewriter desk will not accommodate the copyholding member when in such raised position. Accordingly, the copyholding member and line indicator are mounted in the present instance on a carrier which may be moved relative to the base from a raised operative position to a lowered collapsed position which permits the copyholder to be housed along with a typewriter in the folding cabinet of a typewriter desk.

The support or base for the copyholder comprises an L-shaped structure formed by a rear base member 10 and a forwardly extending base member 11 as shown in Fig. 8. When the present copyholder is positioned for use with a typewriting machine, such as the machine T shown in Fig. 1, the rear base member 10 is disposed along the rear side of the machine and the forwardly extending base member 11 is disposed along the right hand side thereof. This L-shaped base structure for the copyholder is supported on the same surface as the typewriting machine T by three rubber feet 12 carried by the rear base member 10 as shown in Fig. 8 and a similar rubber foot 13 carried by the forward end of the base member 11 as shown in Fig. 1.

In order to occupy less space when being stored or shipped, the forwardly extending base member 11 is adapted to be folded against the rear base member 10. Thus, the forwardly extending base member 11 is pivotally connected to the rear base member 10 by a bifurcated bracket 15 secured to the base member 11, which bracket is connected by a pivot screw 16 to a bracket 17 secured to the rear base member 10 as shown in Figs. 2, 7 and 8. The base member 11 may thus be moved about the axis of the pivot screw 16 to a folded position against the front side of the base member 10, and when the base member 11 is in its forward operative position as shown, the lower end of a spring pressed detent plunger 18 (see Fig. 2) enters a detent hole provided in the base member 10 to resiliently hold the base member 11 in a position extending substantially at right angles to the base member 10.

The copyholding parts of the present construction are mounted on a carrier which is in turn mounted for movement relative to the base between a lowered collapsed position and a raised operative position as previously pointed out. This carrier comprises a rear sheet metal plate 20 which is mounted for vertical movement on a pair of spaced guide posts 22 which are fixed at their lower end to the rear base member 10. The carrier plate 20 is provided with lateral extensions 23 at the lower end thereof which are curved to partially embrace their respective posts 22, and associated retaining pieces 24 are secured to the inner surface of the plate 20. These retaining pieces are likewise curved to partially embrace the opposite portions of the posts 22 as shown in Figs. 2 and 7. The carrier plate 20 is thus mounted to move on the guide post 22 between its lowered collapsed position shown in Fig. 1 and its raised operative position shown in Fig. 2.

Releasable latching means are provided for holding the carrier plate 20 in its operative position, and comprise a pair of latches 26 which are pivotally mounted on respective shouldered screws 27 carried by the plate 20. The screws 27 are retained by associated nuts 28 as shown in Fig. 6, and the latches 26 are spaced inwardly from the carrier plate 20 by associated collars 29. Each of the latches 26 is provided with an inwardly extending arm which is pivotally connected to the lower end of a companion offset link 30. The upper end of each of the links 30 is pivotally connected to the inwardly extending end of a companion latch releasing lever 33 pivotally mounted at 34 on the inner surface of the carrier plate 20. Springs 36 exert a downward pressure on each of the links 30 to resiliently hold each of the latches 26 in a position wherein a forwardly extending lug at the lower end of each of the latches engages a shoulder 37 formed by an annular groove at the upper end of each of the guide posts 22.

The latches 26 are thus effective to normally hold the carrier in its raised operative position on the guide posts 22. The outer end of each of the latch releasing levers 33 is provided with an offset finger piece 40 shown more particularly in Fig. 6, and the carrier may be readily moved to its lower position by pressing downwardly on each of the finger pieces 40 to move the lower end of the latches 26 clear of the shoulders 37 against the force of the spring 36. In order to facilitate the raising and lowering of the carrier, a pair of arms 42 are fixedly secured at 43 to the carrier plate 20. These arms 42 are positioned directly beneath the respective latch releasing levers 33, and the arms 42 are provided with respective offset finger pieces 44 which are generally the same shape as the finger pieces 40 but reversely disposed. When the carrier is raised to its operative position with the aid of the arms 42, the lower ends of the latches 26 slide along the insides of the guide posts 22 and move outwardly under the force of the springs 36 when the carrier reaches its fully raised position to retain such position by engagement with the shoulders 37. A stop arm 46 is secured by a companion screw 47 at the upper end of each of the guide posts 22, and these stop arms are engaged by the nuts 28 to limit the upper movement of the carrier.

The top and bottom edges of the carrier plate 20 are bent forward to form flanges as shown in Figs. 3 and 4, and a front cover plate 50 is pro-

vided with rearwardly extending top and bottom flanges which overlap these forwardly extending top and bottom portions of the rear carrier plate 20. A pair of vertical guide rods 52 are mounted in spaced parallel relation between the rear carrier plate 20 and the cover plate 50, and screws 53 pass through openings in the top and bottom flanges of the plate 20 and cover 50, which screws are threaded into the ends of the guide rods 52 to hold these parts of the carrier in their assembled relation.

In the present copyholder, the copy sheets are moved with relation to a line finder or indicator mounted on the carrier as previously described. However, from the broader aspects of the present invention, it is to be understood that the copy sheets could be mounted stationary on the carrier and the line indicator could be arranged to be moved with relation thereto.

The specific form of line indicator shown in the present drawings comprises a horizontally disposed strip 55 shown particularly in Figs. 1, 3 and 4. The strip 55 is shown as being of sheet metal, but it may be found preferable to use a semi-transparent or translucent material such as colored Celluloid. The lower edge of the strip 55 is suitably attached to a horizontally disposed bail rod 56 and in the present instance, the lower edge of the strip 55 is bent around the rod 56 in a manner to permit the strip 55 to be adjustably turned about the rod but to grip the rod with sufficient tension to retain its adjusted position thereon. The ends of the bail rod 56 are bent downward and then inward as shown in Figs. 1 and 2. The inwardly extending ends of the rod 56 are frictionally retained in sockets formed in brackets 57 by clamping members 58 secured to the respective brackets by screws 59. The brackets 57 are secured at 60 to the inside surface of the carrier plate 20. The screws 59 are adjusted to grip the lower ends of the rod 56 with sufficient tension to allow the bail rod to be adjusted to obtain the desired position of the line indicator and to frictionally hold it in the adjusted position.

The means for advancing the copy sheet past the line indicating strip 55 is shown in the accompanying drawings as a copyholding member 65 mounted for bodily movement relative to the carrier. However, it is to be understood that from the broader aspects of the present invention, other well known means may be employed for moving the copy sheet with relation to the carrier and line indicator. For example, a roller feeding mechanism of various types well known in the art could be employed for this purpose.

The copyholding member 65 in the present instance is in the form of a rectangular sheet metal plate which is reinforced by rearwardly bent flanged portions around its edges. The copyholding plate 65 is mounted for vertical movement on the guide rods 52 by a bracket 66 secured to its rear surface at the lower end portion thereof. Referring to Figs. 3 and 4, it may be seen that each end of the bracket 66 is provided with two rearwardly extending ear portions in vertically spaced relation. These ear portions of the bracket 66 are provided with eyelets 67 which receive the guide rods 52, whereby the copyholding plate 65 is mounted to move freely along the vertical guide rods. As may be seen in Figs. 2, 4, 6 and 7, the inwardly extending ears on the brackets 66 pass through the respective vertically disposed slots 68 in the carrier cover plate 50 to permit the copyholding member 65 to move verti-

ecally with relation to the carrier. In order to maintain free movement of the eyelets 67 along the guide rods 52, a collar 69 of felt or like material may be provided on each of the guide rods, which collar may be saturated with a lubricant and arranged to slide on the rods to lubricate and clean the guide rods.

The means for retaining copy sheets on the front face of the copyholding plate 65 may be of substantially the same construction as shown in Patent No. 1,719,422 granted July 2, 1929. Referring particularly to Figs. 1, 2 and 4, it may be seen that this construction includes a bail 75 extending horizontally across the top portion of the copyholding plate 65, and the inwardly extending ends of this bail are received in slots provided in opposite end portions of a bracket 76 extending along the upper edge portion of the plate 65. An arm 78 is secured in a channel in each end of the bail 75, and springs 79 are provided between each of the arms 78 and the top portion of the bracket 76 to normally press the top of the bail inwardly toward the copyholding plate. A plurality of rubber rings 80 are arranged on the horizontal portion of the bail 75. Thus, a copy sheet, or stenographer's note book may be placed beneath the rubber rings 80 and securely clamped against the plate 65 by the force of the springs 79. When it is desired to insert or remove material to be copied, the bail 75 may be swung forward to a position wherein the arms 78 engage the rear surface of the bracket 76 and the lower ends of the springs 79 are thus moved across the pivotal axis of the bail 75 to retain the bail in this forward released position.

Means are also provided for holding transcribed copy sheets in a turned position over top of the copy carrying plate 65. This means in the present instance is shown as a spiral contractile spring 82 extending across the top of the horizontal portion of the bracket 76. The ends of the spring 82 are attached to the respective end portions of the bracket 76, and the spring is provided with a certain amount of tension so that sheets after they are copied may be placed beneath the spring to be held thereby in a turned position over the top of the copy carrying member 65.

The means for controlling the upward and downward movement of the copy carrying plate 65 with relation to the carrier includes mechanism carried in part by the carrier and in part by the stationary base members. The portion of this mechanism carried by the stationary base members includes a forwardly extending lever 85 which is pivotally mounted at 86 to an upstanding portion of the forwardly extending base member 11 as shown in Figs. 1 and 2. A handle 88 is mounted at the forward end of the lever 85, and this handle may be adjusted along the lever 85 to the desired position with relation to a typewriting machine T. The adjusted position of the handle 88 on the lever 85 may be retained by tightening a clamping screw 89 provided on the handle.

The rear portion of the lever 85 is bent inward and is provided with a reduced semi-circular end forming a ball and socket type connection with a bifurcated member 92 carried by the end of an arm 93. The arm 93 is pivotally mounted at 94 to an upstanding portion on the rear base member 10 as shown in Fig. 2. It will be noted that the ball and socket connection between the lever 85 and the arm 93 is normally positioned directly above the pivot screw 16 connecting the

two base members 10 and 11. Accordingly, the lever 85 merely pivots about its connection with the arm 93 when the forwardly extending base member 11 is folded against the rear base member 10.

The portion of the mechanism for controlling the upward and downward movement of the copyholding member which is mounted on the carrier may be generally similar to that disclosed in Patent No. 1,837,027 issued December 15, 1931. This mechanism includes a lifting rod 97 fixedly secured at 98 to the upper bracket member 76 on the copyholding plate 65, and the lower end of the rod 97 is retained against displacement laterally by an extension 99 on the lower guide bracket 66 at the bottom of the copyholding plate. The extension 99 passes through an elongated vertical slot 101 in the carrier cover plate 50 and the upper end of the rod 97 passes through an opening in the top flange portion of the rear carrier plate 20.

The upward and downward movement of the copyholding plate is effected through a control rod 103 mounted for longitudinal movement on the carrier. The upper end of the control rod 103 passes through an opening in the top flange of the carrier plate 20, and the lower end of the control rod is retained against lateral displacement by a guide bracket 104 secured to the carrier plate 20 to partially embrace the rod 103 as shown in Fig. 5. In order to provide a substantially noiseless and frictionless guide for the upper ends of the rods 97 and 103, a fiber plate 105 is secured to the lower surface of the flange at the upper end of the carrier plate 20 as shown in Figs. 2, 3 and 5. This fiber plate is provided with bearing openings receiving each of the rods 97 and 103, and the metal of the carrier plate flange is cut away around these bearing openings to be out of contact with the rods.

The control rod 103 is moved either upward or downward from its illustrated position to control movements of the copyholding plate 65, and for this purpose an interconnecting means is provided in the form of a link 110 pivotally connected at 111 to the intermediate portion of the arm 93 on the base member 10, and the upper end of the link is operatively connected to the lower end of the rod 103 when the carrier is in its raised operative position. Referring to Figs. 2 and 7, it may be seen that the connection between the upper end of the link 110 and the rod 103 comprises a clip 114 attached by a screw 115 to the lower end of the rod, and the clip carries a shouldered screw 116 threaded into an enlarged retaining washer 117. The intermediate portion of the screw 116 passes through an elongated slot 118 extending substantially the entire length of the link 110, and the upper end of the slot 118 extends laterally toward the rod 103 to provide shouldered portions disposed above and below the body of the screw 116 when the carrier is in its raised operative position as shown in Fig. 2 for example. A leaf spring member 120 is secured by the screw 115 in a position to resiliently hold the upper end of the link 110 in a position wherein the shoulders formed by the upper end of the slot 118 are disposed above and below the screw 116 and thereby operatively connect the lever 93 with the control rod 103.

It will now be clear that a manual depression of the handle 88 will cause an upward movement of the control rod 103 through the arm 93 and link 110. This upward movement of the rod 103

is transmitted to the copyholder rod 97 through a lifting clutch member 125 which is formed of a rigid piece of channel-shaped metal having a slotted end portion which straddles the control rod 103 as shown in Fig. 6. A pin 126 is carried by the rod 103 directly beneath the lifting clutch member 125, and a retaining pin 127 is also carried by the rod just above the clutch member 125.

The copyholder rod 97 extends through a rectangular aperture in the lifting clutch member 125, and clutch jaws 130 are mounted in this rectangular aperture to engage opposite sides of the rod 97. Each of the jaws 130 comprises a metal casing having a non-metallic lining or filler of the type specifically disclosed in Patent No. 1,837,027. Thus, when the control rod 103 is moved upward by a depression of the handle 88, the lifting clutch member 125 receives a slight angular movement causing the clutch jaws 130 to grip the copyholder rod 97 so that the copyholding plate 65 is moved upward by the continued upward movement of the rod 103.

This upward movement of the copyholding plate 65 moves the copy sheet past the line indicator 55, and in order that this movement may be adjusted to accord with different extents of line spacing on various copy sheets, an adjustable stop is provided for limiting the operation of the lever 85. Referring to Figs. 1, 2, and 8, it may be seen that this adjustable stop is mounted on a bracket 134 secured to the rear portion of the base member 11. The bracket 134 extends upward at the side of the rearward end of the lever 85, and a stop member 135 is mounted for vertical adjustment on the bracket 134. The upper end of the stop member 135 is bent inward and is provided with a cushioned stop contact 136 which is positioned to be engaged by the rearward end of the lever 85 when the handle 88 is moved downward. The desired position of adjustment of the stop member 135 may be retained by a clamping screw 137 which passes through a vertically disposed slot in the bracket 134 and is threaded into the stop member 135. Thus, the position of the stop member 135 may be adjusted to afford an extent of movement of the lever 85 which will result in the desired extent of line spacing movement of the copy sheet with respect to the line finder 55.

A returning spring 140 is provided between the arm 93 and the rear base member 10 as shown in Fig. 2. This spring acts to return the lever 85, arm 93 and rod 103 to their normal positions when the downward pressure on the handle 88 is removed. During this downward return movement of the rod 103, the end of the lifting clutch member 125 which is connected to the rod 103 is moved downward toward a straightened position which releases the clamping engagement of the clutch jaws 130 with the copyholder rod 97. Thus, the return downward movement of the rod 103 does not cause a corresponding downward movement of the copyholding member through the rod 97.

A releasable holding clutch mechanism is provided for normally retaining the copyholder in the position to which it is raised through the lifting clutch member 125. This holding mechanism comprises a holding clutch member 142 which is generally similar to the lifting clutch member 125. One end of the member 142 is bifurcated to straddle the control rod 103 in the same manner as the member 125 and the other end is likewise provided with a rectangular shaped aperture in which a pair of clutch jaws 75

143 are mounted to engage opposite sides of the rod 97. The intermediate portion of holding clutch member 142 between the rods 97 and 103 is supported on the upper edge of an inwardly extending portion of a bracket 145 which is secured at 146 to the carrier plate 20. A contractile spring 147 extends between the bracket 145 and the intermediate portion of the clutch member 142 to normally hold it in a position wherein the clutch jaws 143 are in clamping engagement with the rod 97 to prevent downward movement thereof. However, when the rod 97 is moved upward through the lifting clutch member 125, the clutch member 142 receives a slight pivotal movement about the bracket 145 until the clutch jaws 143 do not effectively engage the rod 97 and thus permit the rod 97 to move upward relative thereto. When the upward force on the rod 97 is removed, the tendency of the copyholder to move downward causes the clutch jaws 143 to again engage and hold the rod 97.

When it is desired to lower the copyholding plate 65 on the carrier, the handle 88 may be raised from its normal position to pull downward on the clutch control rod 103. This downward movement of the rod 103 causes the pin 126 to engage the holding clutch member 142 and move it toward a horizontal position against the force of the spring 147. This movement of the member 142 releases the normal gripping engagement of the clutch jaws 143 with the rod 97 thereby permitting the copyholding plate 65 to move downward by gravity to its normal or first-line copying position with respect to the carrier.

35 A retarding mechanism is provided in the present copyholder in order to prevent the copyholding plate 65 from gaining undue momentum in its downward movement. This retarding means in the present instance comprises a retarding clutch member 151 having clutch jaws 152 carried thereby in contact with opposite sides of the rod 97. One end of the retarding member 151 is mounted at 153 to the lower side of the top flange portion of the carrier plate 20, and the other end of the member 151 carries a threaded rod 154 extending upward through an aperture in the flange of the carrier plate. An expansion spring 155 is provided on the threaded rod 154 between the retarding member 151 and the flange of the carrier plate 20 and a knurled adjusting nut 156 is threaded on the upper end of the rod 154 to normally engage the upper surface of this carrier plate flange. The slight angular disposition of the member 151 causes a slight gripping action between the jaws 152 and the rod 97 to retard the downward movement of the copyholding plate 65, and the extent of this retarding action may be varied by turning the nut 156 in one direction or the other to accordingly vary the angular disposition of the member 151.

The copyholding plate 65 with the copy sheets or other transcribing material attached thereto is thus retarded in a downward movement to normal position on the carrier, and shock absorbing means are provided to arrest the copy carrying plate in its normal position with a minimum of noise and shock. Thus as may be seen in Figs. 2 and 4, a coiled expansion spring 158 is placed around the bottom portion of each of the guide rods 52. The lower ends of these springs 158 rest on the lower flange of the carrier plate 20, and as the copyholding plate 65 reaches its lowermost normal position, the upper ends of the springs 158 are engaged by the lower portion

of the bracket 66 on the copyholding plate as shown in Fig. 4 to resiliently arrest the downward movement of the copyholding plate with a minimum of noise and shock.

It will now be understood that when the carrier is in its raised operative position on the guide posts 22, the copy carrying plate 65 may be moved relative thereto intermittently in an upward direction by depressing the handle 88 and may be returned downward to its normal position by lifting the handle. In order to control this movement of the copyholding plate on the carrier, the connecting link 110 has been arranged to transmit both upward and downward movement from the arm 93 to the rod 103 when the carrier is in its raised operative position. Accordingly, the operative connection between the link 110 and the rod 103 must be interrupted when it is desired to move the carrier to its lowered collapsed position with relation to the base.

In accordance with the present invention, means are provided for automatically interrupting this operative connection between the link 110 and the rod 103 when the latch members 26 are operated to a released position enabling the carrier to be lowered to its collapsed position. Referring to Figs. 2 and 7, a slide 164 is mounted for horizontal movement on the inner side of the carrier plate 20 by headed rivets 165 passing through respective slots in the slide 164. One end of the slide 164 is bent laterally to coact with the edge of the link 110 but is normally held out of contact therewith by a contractile spring 166 extending between the slide 164 and a pin 167 secured to the carrier plate 20. The outer portion of the slide 164 extends upward and is provided with a laterally bent end which normally engages the edge of the lower portion of the left-hand releasable latch member 26. Thus, when the latch members 26 are moved inward out of engagement with the shoulders 37 of the guide posts 22 by depressing the finger pieces 40 of the latch releasing levers, the left hand latch 26 moves the slide 164 horizontally to engage the edge of the link 110 and causes a movement of the upper end of the link toward the rod 103 against the force of the spring 120. This movement of the upper end of the link 110 positions the vertical portion of the slot 118 beneath the body portion of the connecting screw 116 so that the carrier may be moved downward along the guide post 22 with the screw 116 moving in the vertical portion of the slot 118.

In this manner, the link 110 which normally connects the arm 93 with the rod 103 for movement in either direction when the carrier is in its raised operative position is automatically disconnected by operation of the releasable latch mechanism to permit the carrier to be readily lowered to its collapsed position. When it is desired to again raise the carrier to its operative position, the screw 116 slides in the slot 118 until the carrier is latched in its operative position, whereupon the spring 120 moves the upper end of the link 110 back to its illustrated position which operatively connects the arm 93 and rod 103.

In order to place the present copyholder in its fully collapsed condition, it is not only necessary to move the carrier downward with relation to the base, but it is also necessary to have the copyholding member in its normal position with relation to the carrier. Accordingly, means are provided in accordance with the present invention for automatically returning the copyholding

member to its normal or lowermost position with relation to the carrier when the carrier is released for movement to its collapsed position with relation to the base.

5 Referring to Figs. 2 and 6 a lever 170 is pivotally mounted at its central portion on the inner surface of the carrier plate 20 by a headed rivet 171. One end of this lever 170 is bent laterally to normally engage the upper edge of the inner end 10 portion of the right-hand latch releasing lever 33. The other end of the lever 170 is also bent laterally to extend above the bifurcated end of the holding clutch member 142. Thus, when the latches 26 are released to permit downward 15 movement of the carrier to its collapsed position, the lever 170 is rocked about its pivot by the releasing movement of the right-hand latch releasing lever to thereby move the holding clutch member 142 toward its horizontal position. This movement of the member 142 releases the clamping engagement of the jaws 143 with the rod 97 and permits the copyholding plate 65 to move downward to its normal position as previously described.

20 The present collapsible copyholder may if desired be secured permanently in the usual manner to the supporting surface of a folding cabinet of a typewriter desk. However, means are provided which cooperate with a typewriting machine, such as T shown in Fig. 1, to releasably retain the copyholder in position against accidental displacement, thereby making it unnecessary to permanently secure the copyholder to the supporting surface.

25 The means shown in the present instance for retaining the forwardly extending base member 11 is fully disclosed in Patent No. 2,155,246 issued April 18, 1939. This retaining means may be generally described as comprising a carrier 175 mounted for vertical movement in a slot 176 in the base member 11. A rubber covered retaining arm 178 is pivotally mounted on the carrier 175 for movement between its position shown in Fig. 8 and a collapsed position against the inside 30 surface of the base member 11. Spring means, not shown in the present drawings, are provided to act upward on the carrier 175 and to hold the arm 178 in engagement with the lower edge of the typewriter side plate. The carrier 175 is so 35 arranged that any force tending to raise the base member 11 from its supported surface is resisted by the engagement of the arm 178 with the typewriting machine to cause a binding action between the carrier and the base member 11. This 40 retaining means may be readily released by a downward pressure on the carrier member 175, and it is arranged to cooperate equally well with different typewriting machines regardless of the 45 distance between the lower edge of the side plate and the supporting surface.

45 Means are also provided for retaining the left-hand rear portion of the copyholder against displacement with relation to the typewriting machine. This retaining means may if desired, be 50 the same as that provided on the base member 11, but in the present instance a specifically different means has been shown. Referring to Figs. 2 and 8, it may be seen that a rubber covered retaining arm 180 is mounted on an adjustable slide 55 member 181 for pivotal movement thereon between a forwardly extending position as shown and a folded position along the base member 10. The slide 181 is mounted for vertical adjustment 60 along an upward extension 182 on the base member 10, and the arm 180 is normally positioned in 65

engagement with the lower edge of the rear cover plate of the typewriting machine. The slide 181 is retained by a clamping screw 183 against displacement from its adjusted position on the extension 182.

An improved copyholder has thus been provided which is comparatively simple and inexpensive to manufacture and yet highly effective and reliable in use. A particular feature of the present copyholder is the arrangement of the copyholding member on a carrier which may be moved with relation to its base between a raised operative position and a lowered collapsed position. This feature involves the provision of improved mechanism for controlling the movements of the copyholding member with relation to the carrier, which mechanism is jointly carried by the base and the carrier with interconnecting means arranged to automatically establish an operative connection between the controlling mechanism on the base and the controlling mechanism on the carrier when the carrier reaches its raised operative position and having means for automatically interrupting this operative connection when the carrier is released for movement to its lowered collapsed position.

Another feature of the present copyholder is the provision of means for automatically returning the copyholding member to its normal position with relation to the carrier as the carrier is moved to its collapsed position. These features cooperate to provide a copyholder which may be easily and quickly changed from a condition affording normal operation to a collapsed condition permitting it to be housed together with a typewriting machine in the folding compartment of a typewriter desk.

The invention claimed is:

1. In a copyholder, the combination of a base, a pair of spaced guide posts extending upward from said base, a carrier mounted for movement on said guide posts between a lowered collapsed position and a raised operative position, a pair of releasable latches for holding said carrier in raised operative position, a copyholding member mounted on said carrier for vertical movement relative thereto, actuating means for said copyholding member carried jointly by said base and said carrier and having interconnecting means normally engaged when the carrier is in operative position, releasable holding means for preventing downward movement of said copyholding member relative to said carrier, means controlled by one of said pair of latches for disengaging said interconnecting means, and means controlled by the other of said pair of latches for releasing said holding means.

2. In a copyholder, the combination of a support, a carrier mounted for movement on said support between a collapsed position and an operative position, a pair of releasable latches for holding said carrier in operative position, a copyholding member mounted on said carrier for movement relative thereto, actuating means for said copyholding member carried jointly by said support and said carrier and having interconnecting means normally engaged when the carrier is in operative position, releasable holding means for preventing movement of said copyholding member relative to said carrier, means controlled by one of said pair of latches for disengaging said interconnecting means, and means controlled by the other of said pair of latches for releasing said holding means.

3. In a copyholder, the combination of a sup-

port, a carrier movable on said support between a collapsed and an operative position, releasable latching means for holding said carrier in its operative position, a copyholding member mounted for movement on said carrier, actuating means carried jointly by said support and said carrier and having connecting means normally engaged when the carrier is in operative position, releasable holding means for said copyholding member, and means controlled by said latching means for disengaging said connecting means and releasing said holding means when the latching means is released.

4. In a copyholder, the combination of a support, a carrier mounted for movement on said support between a collapsed and an operative position, copy holding and line indicating members mounted on said carrier, one of said members being mounted for movement relative to said carrier, actuating means for said movable member on said carrier, said actuating means being carried in part by said support and in part by said carrier with releasable connecting means effective when said carrier is in operative position, releasable holding means for preventing retrograde movement of said movable member relative to said carrier, and means for releasing said connecting means and said holding means.

5. In a copyholder, the combination of a support, a carrier mounted for movement on said support between an operative and a collapsed position, releasable latching means for holding said carrier in operative position, copy holding and line indicating members mounted on said carrier, one of said members being mounted for movement relative to said carrier, controlling means for said movable member on said carrier, said controlling means being carried in part by said support and in part by said carrier with releasable interconnecting means, engaging means acting on said interconnecting means to automatically couple the part of said controlling means carried by the support with the part of the controlling means carried by the carrier when the carrier is moved to operative position, and means controlled by said latching means for releasing said interconnecting means upon release of the latching means.

6. In a copyholder, the combination of a support, a carrier mounted for movement on said support between an operative and a collapsed position, releasable latching means for holding said carrier in operative position, copy holding and line indicating members mounted on said carrier, one of said members being mounted for movement relative to said carrier, controlling means for said movable member on said carrier, said controlling means being carried in part by said support and in part by said carrier with releasable interconnecting means arranged to automatically couple the part of said controlling means carried by the support with the part of the controlling means carried by the carrier when the carrier is moved to operative position, and means controlled by said latching means for releasing said interconnecting means upon release of the latching means.

7. In a copyholder, the combination of a base, a pair of spaced guide posts extending upward from said base, a carrier mounted for movement on said guide posts between a lowered collapsed position, and a raised operative position, releasable latching means for holding said carrier in raised operative position, a copyholding member mounted on said carrier for substantially vertical

movement relative thereto, actuating means mounted on said base, means operatively connecting said actuating means with said copyholding member when said carrier is in its raised operative position, and means controlled by said releasable latching means for disconnecting said copyholding member from said actuating means when the latching means is released.

8. In a copyholder, the combination of a support, a carrier mounted for movement relative to said support between a collapsed and an operative position, releasable latching means for holding said carrier in one of said positions, copy holding and line indicating members mounted on said carrier, one of said members being mounted for movement relative to said carrier, actuating means for said movable member on said carrier, said actuating means being carried jointly by said support and said carrier and having interconnecting means normally engaged when the carrier is in operative position, and means controlled by said latching means for disengaging said interconnecting means upon release of the latching means.

9. In a copyholder, the combination of a support, a carrier mounted for movement relative to said support between a collapsed and an operative position, copyholding and line indicating members mounted on said carrier, one of said members being mounted for movement relative to said carrier, controlling means for said movable member on said carrier, said controlling means being carried in part by said support and in part by said carrier with releasable connecting means arranged to couple the part of said controlling means carried by the support with the part thereof carried by the carrier when the carrier is moved to one position relative to said support, and means for releasing said connecting means to permit movement of said carrier to another position relative to said support.

10. In a copyholder, the combination of a base,

5 a pair of spaced guide posts extending upward from said base, a carrier mounted for movement on said guide posts between a lowered collapsed position and a raised operative position, releasable latching means for holding said carrier in its operative position, a copyholding member mounted on said carrier for movement relative thereto, means for intermittently raising said copyholding member relative to said carrier, releasable holding means for normally preventing downward movement of said copyholding member relative to said carrier, and means controlled by said releasable latching means for releasing said holding means when the latching means is released.

10 11. In a copyholder, the combination of a support, a carrier mounted for movement on said guide posts between a collapsed position and an operative position, releasable latching means for holding said carrier in its operative position, a copyholding member mounted on said carrier for movement relative thereto, means for intermittently moving said copyholding member relative to said carrier, releasable holding means for normally preventing retrograde movement of said copyholding member relative to said carrier, and means controlled by said releasable latching means for releasing said holding means when the latching means is released.

15 12. In a copyholder, the combination of a support, a carrier mounted for movement on said support between a collapsed and an operative position, releasable latching means for holding said carrier in one of said positions, copy holding and line indicating members mounted on said carrier, one of said members being mounted for movement relative to said carrier, releasable holding means for preventing retrograde movement of said movable member relative to said carrier, and means controlled by said latching means for releasing said holding means.
